UNITED STATES PATENT OFFICE.

SUSAN G. BERGH, OF WEST NEW YORK, NEW JERSEY.

CLOTHES-POUNDER.

1,233,639.

Specification of Letters Patent. Patented July 17, 1917.

Application filed October 24, 1914. Serial No. 868,375.

To all whom it may concern:

Be it known that I, SUSAN G. BERGH, a citizen of the United States, residing at West New York, in the county of Hudson and State of New Jersey, have invented certain new and useful Improvements in Clothes-Pounders, fully described and represented in the following specification and the accompanying drawings, forming a part 10 of the same.

This invention relates to clothes pounders, or clothes washers of that class in which the washer comprises a body or head and an upwardly extending handle, and in which the 15 body or head is formed or constructed to promote the passage of water through the clothes when the washer is moved up and down in the water containing the clothes.

The object of the invention is to provide 20 an improved washer of this kind, and more particularly to provide one which shall be easy to use and highly efficient in operation, durable, and of simple and inexpensive construction.

25 A full understanding of the invention can best be given by a description in connection with drawings showing an approved embodiment of the invention, and such a description will now be given in connection 30 with the accompanying drawings, in which

Figure 1 is a view in side elevation of an approved embodiment of the invention, the handle being shown as broken off;

Fig. 2 is a bottom plan view of the 35 pounder head; and

Fig. 3 is a section taken on line 3—3 of Fig. 1 looking downward.

Referring to the drawings, the washer or pounder comprises a pounder head 10 and 40 an upwardly extending handle 11. The pounder head as shown is formed from a solid block of wood or other suitable material of suitable density, and is shaped round in cross section with an inwardly sloping 45 upper part. The bottom of the pounder head is flat but formed with intersecting grooves or channels 12 and 13 extending clear across the bottom and through the sides. These channels should be of substan-

50 tial depth to provide for the flow or passage of water therethrough, and in a pounder having a head of a little less than six inches in diameter and about seven and a half inches high, which is a size which I have 55 found well suited for general use, the grooves or channels are best made in the

number and arrangement and of about the proportionate size shown. Extending upward from the points of intersection of the channels 12 and 13 are interior channels or 60 passageways 14 which a short distance above the bottom channels turn outwardly and open through the sides of the pounder head. The outwardly extending portions of the channels 14 are in the construction shown, 65 and most desirably, divided or branched as shown best in Fig. 3. The branched outwardly extending portions 14^a which may be, though they are not necessarily, of the same diameter as or of greater diameter than 70 the upwardly extending portions of the channels, increase the interior space which is open when the ends of the passages opening through the sides of the pounder head are above the water and closed when the 75 ends of the passages are below the water level. The head as shown is also formed with a central through passage or bore 15, the upper end of which provides a socket to receive the lower end of the handle 11, and 80 the lower portion of which provides an upwardly extending passage open only at its lower end through the bottom of the pounder head. The handle of wood or other suitable material may be of any suitable length 85 but is usually made about three feet long.

The washer is used in the same way as other washers of this kind, that is, by being worked up and down on the clothes in the water. The alternate pressure or down 90 strokes and suction or up strokes result in forcing the water with more or less air through the clothes, and a comparatively quick and very thorough washing of clothes, including in this term all sorts of light and 95 heavy body clothes, bed clothes, table linen and other pieces of fabric, is thus secured. On the downward movement of the washer, as the clothes are pressed downward the water flows against the clothes through the 100 bottom channels 12 and 13 and also flows upwardly through the clothes into the bottom channels and up into the channels 14. On the return or upward stroke the clothes are lifted by suction with the pounder until 105 the side openings are raised above the surface of the water, whereupon the suction will be broken and as air enters the side openings the water carried in the passages 14 will be discharged downwardly against the clothes 110 from the passages 14.

By making the pounder head of a solid

block of wood with the channels and passages as shown, I provide a washer having both considerable weight and considerable buoyancy or floating power, that is, on the one hand, the pounder head is heavy as compared to the sheet metal washers commonly in use, and on the other hand, its displacement is also relatively large, and when made as shown in the drawings of a suitable wood 5 the relation between the weight and the displacement of the pounder head will be such that with the handle extending upward the pounder will float in water with the major portion, usually about two-thirds, of the 10 head submerged. This is of great advantage in using the washer, since the weight gives a momentum on the down stroke which makes any hard fatiguing downward pushing of the washer unnecessary, and the lifting 15 or floating power of the head serves to immediately start it upward again after the completion of the down stroke, thus materially lessening the power which would otherwise have to be applied in raising the 20 pounder. The washer is thus very much easier to use and the work of washing is materially lightened as compared to that with a washer of this kind which does not have the weight and relative buoyancy of my 25 washer.

This feature of the invention may, of course, be embodied in a washer having a pounder head made otherwise than of a solid block of wood or other material of suitable 30 density. In making the pounder head of a solid block of wood or other material, the head need not necessarily be made of a single integral piece, although in making the head of a solid block it is desirable for practical 35 reasons to form the block from a single integral piece. In using the term "wood" I do not mean to include such unusual and heavy woods as will not float or which have only a slight buoyancy. I find it most desirable 40 to use a fairly buoyant wood such as ash or so-called white wood.

Another advantage of forming the pounder head of wood or similar material is that it will not corrode, and the washer thus has a 45 maximum durability and is practically indestructible.

It is to be understood that the invention is not to be limited to the exact shape of the head and arrangement of channels and passages as in the illustrative embodiment 50

shown and to which the foregoing description has been largely confined, but that it includes changes and modifications thereof within the claims.

What is claimed is:

1. A clothes pounder, comprising a pounder head and an upwardly extending handle, the head being formed of wood and shaped with an inwardly sloping upper part and having a flat bottom face formed with channels extending outwardly through the sides and having a plurality of interior passages extending upward from said channels and opening outward through the sides of the head. 60

2. A clothes pounder, comprising a pounder head and an upwardly extending handle, the head having a bottom face formed with intersecting channels which extend outward through the sides of the head, and the head having a plurality of interior 65 passages extending upward from the points of intersection of said channels and opening outward through the sides of the head. 70

3. A clothes pounder, comprising a pounder head and an upwardly extending handle, the head having a bottom face formed with intersecting channels which extend outward through the sides of the head, and the head having a plurality of interior 75 passages extending upward from the points of intersection of said channels and branched passages leading from the upper ends of said passages and opening outward through the sides of the head. 80

4. A clothes pounder, comprising a pounder head and an upwardly extending handle, the head being formed with channels in its bottom face extending outwardly through the sides and with a plurality of 85 interior passages extending upward from said channels and opening outward through the sides of the head, and the head being of such weight with relation to its displacement that with the handle extending upward the pounder will float in water with the major portion of the head submerged. 90

In testimony whereof I have hereunto set my hand in the presence of two subscribing witnesses.

SUSAN G. BERGH.
